LEWIS A. DARLING, OF PHILADELPHIA, PENNSYLVANIA, ASSIGNOR TO ELECTRIC SERVICE SUPPLIES COMPANY, OF PHILADELPHIA, PENNSYLVANIA, A CORPORATION OF PENNSYLVANIA.

CONTROLLING VALVE FOR ENGINES ACTUATED BY STEAM OR OTHER MOTIVE FLUID.

Application filed December 19, 1918. Serial No. 267,464.

To all whom it may concern:

Be it known that I, LEWIS A. DARLING, of Philadelphia, in the county of Philadelphia and State of Pennsylvania, have invented certain new and useful Improvements in Controlling Valves for Engines Actuated by Steam or Other Motive Fluid, whereof the following is a specification, reference being had to the accompanying drawings.

My invention is especially adapted for use as a controlling valve for such a motor device as a steam turbine generator, the system comprising in this instance, a speed governor, whereby the valve is moved automatically to vary the supply of steam to the turbine wheel.

In the accompanying drawings, Fig. I, represents a vertical axial section through the valve and adjacent portion of the casing, showing, in side elevation, the arm which is rocked by the governor device.

Fig. II, is a transverse section of the valve, and its enclosing sleeve on the line II, II, of Fig. I.

Fig. III, is a similar transverse section on the line III, III.

Fig. IV, is an axial sectional view through a modified form of the device.

Fig. V, is an axial sectional view through another modified form thereof. Certain elements are common to all these forms; thus broadly speaking, the embodiments shown all comprise group of parts that affords a mounting for the valve proper and the associated operating parts, and is itself adapted to be mounted and secured in an opening or bore in a casing. This system comprises a sleeve that serves as case for the valve device, and is provided with internal passages or ports located at different longitudinal intervals, one of which passages receives the steam from the source of supply, whilst the other delivers the same to the turbine wheel.

The opening or bore in which the sleeve above referred to is mounted, extends so as to include overlapping portions of these passages, and the sleeve itself contains a plunger or piston valve, movable longitudinally or endwise with relation thereto, the valve be-

ing actuated in one direction by means of an externally protruding stem co-operating with the governing mechanism, but being moved in the other direction by means of a spring.

Apart from the differences of structural detail, the main difference between the type shown in Fig. I, and those shown in Figs. IV, and V, consists in the fact that the device of Fig. I, is not a completely balanced valve, whilst the devices shown in Figs. IV, and V, are substantially balanced valves.

Referring now to the forms shown in Figs. I, II, and III, 1, indicates a portion of the casing structure for such a device as a steam turbine generator, which casing may be part of, or separate from the casing proper of the turbine. Connected with this

casing is a supply pipe 2, which leads from any convenient source, and which may be provided with a strainer 20. A lateral inlet passage 3, is formed in the casing, and communicates with the passage 2. Also formed in the casing, but in another plane from that of the passage 2, is an outlet passage 4, which is adapted to deliver the steam to the nozzle for the turbine. As will be apparent from Fig. I, whilst these passages are situated in different planes, they are disposed in overlapping relation to one another.

Another passage 21, is also formed in the casing at a still different plane, and extends above the overlapping region of the passages 3, and 4, said passage 21, communicating with a region of suitable given pressure, in this instance the passage 4, through a vertical passage 22. An opening or bore (in this instance cylindrical, and with a vertical axis,) is formed through the casing and intersects the overlapping portions of the passages 3, 4, and 21, said opening being adapted to receive the controlling valve system, which comprises the following parts, viz—

an outer sleeve 5, is threaded into the vertical opening of the chamber, the upper end of said sleeve being located within the passage 21, and being provided with a slot 12, whereby it may be screwed into position, or unscrewed. The sleeve 5, has, it will be seen, a flange at its upper end, so that when screwed home it is held firmly seated and

fixed. The lower end of the sleeve or case 5 protrudes from its bore in the structure 1.

The sleeve 5, has an inner cylindrical axial chamber 6, preferably similar in diameter 5 throughout the greater portion of its extent, but terminating at the bottom in a reduced opening, which permits the passage of the valve operating stem or plunger 16, which will be described later on.

10 Said sleeve 5, is provided with two sets of radial passages preferably arranged at quadrant intervals and staggered, said passages being located respectively opposite to the overlapping regions of the chambers 3, 15 and 4. Thus, the ports 8, afford communication from the supply passage 3, to the interior of the chamber 6, and the ports 7, in a like manner, afford communication to the passage 4.

20 Fitting snugly within the chamber, though capable of free endwise movement therein, is a plunger valve body 9, of generally cylindrical form but having an extended cut-away portion, adjacent to its central region, 25 as indicated at 10, so as to afford an elongated interspace between the wall of the sleeve 5 and the valve body, throughout a region corresponding with the length of the cut-away portion.

30 When, therefore, the valve body 9, is located at such a vertical height within the sleeve as to bring the reduced portion into partial or complete communication with the ports 7, and 8, a controlled communication 35 is established between said groups of ports and consequently between the supply and delivery passages.

The reduced portion of the valve body terminates at each extremity, in a well defined 40 shoulder, such as 11, which is adapted to present a symmetrical edge to the opening when the valve is in an open position, and which sharply cuts off the communication when the valve body is in such position that the reduced portion no longer is opposite to 45 the respective groups of ports.

It is obvious that by raising or lowering 50 the valve body, the communication between the supply and delivery passages may be completely controlled from an entirely open position on the one hand, to an absolute closure on the other, and that between these 55 limits a well defined and delicate control of the flow of steam may be effected, so that it can be accurately throttled.

Above the portion of the opening or bore 60 in which the valve sleeve is located, a somewhat larger prolongation of this opening, co-axial therewith, is formed in the top of the casing, into which is threaded a closure in the form of a hollow cap or plug 13, adapted to form a tight joint and co-operate with the sleeve as part of the valve-mounting structure. The valve body is provided with 65 a plunger 16, which, in this instance, is a

separate rod fitting loosely within a cylindrical axial cavity in the body, which cavity is closed at the top and slightly conical at its upper extremity. The upper end of the rod 16 engages the conically concave end 70 of the valve body cavity to actuate the valve 9 in opposition to the spring 15, but is not attached or connected to the valve. The upper extremity of the valve body is somewhat reduced in external diameter, to afford 75 an extension or projection 24 with an approximately conical end, forming a reduced bearing lug. An abutment plate 14, of hollow conical form, with horizontally flanged peripheral portions, rests upon the top of the projection 24, and a coiled spring 15, is interposed between the flanged portion of this abutment member and the under side or bottom of the cap 13, said spring being so arranged as to be somewhat compressed when 80 the cap 13, is screwed into position.

The lower extremity of the plunger 16, operatively engages the governing mechanism or connection, being shown in this instance as resting upon the head 18, of an adjustable screw mounted in the outer extremity of the rock arm 17, of the governing device, a transverse screw 19, being provided to clamp the screw 18, and retain it in any 85 fixed position of adjustment.

From the above description it will be seen that when the actuating member or plunger 16, is raised, or positively shifted by the governing mechanism, the reduced portion of the valve body can be brought into any desired relation to the ports 7, and 8, respectively, so that the flow of steam can be accurately controlled from the fullest area of communication down to a complete 90 cut-off. Conversely, the valve body will be moved downwardly, or in the opposite direction, by the extension of the spring 15, when this action is permitted by the receding movement of the governing arm 17. As 95 above stated, the passage-way 21, within which the sleeve 5, terminates at its upper extremity, communicates by the passage 22, with the passage 4, so that the upper portion of the valve body is under steam pressure 100 corresponding to that which exists at any given moment in the passage 4. The lower extremity of the valve body, however, is subjected to the pressure which exists in the lower end of the chamber 6, and which is 105 in a certain sense, indeterminate, because it depends upon the leakage which may exist at the opening through which the plunger leads at the bottom of the sleeve, as compared with the leakage which exists between 110 the lower extremity of the chamber 6, and the passage 4.

115 It will be noted that in the embodiment shown, the passages are so located as to drain towards the turbine casing, and thus 120 prevent the accumulation of water of con- 125

densation at any point within the system, which is particularly important as against freezing under exposed conditions, and also prevents deterioration from corrosion due to trapped moisture.

Referring now to the type of devices shown in Fig. IV, the general organization is similar to that of Fig. I, the casing being indicated at 31, the supply and delivery 10 passages at 33, and 34, respectively, the upper passage 42 and the sleeve at 35. In this instance, the opening or bore in the casing adjacent to the overlapping region of the passages, is not wholly cylindrical, but is 15 in part slightly conical to receive the correspondingly coned portion 36 of the sleeve or valve case, only the lower portion 37, of the sleeve being cylindrical, and being threaded to engage with the correspondingly threaded lower portion of the opening in the casing.

The sleeve is provided with the ports 38, and 39, respectively communicating with the overlapping regions of the passages 33, and 25 34. The valve body 40, has (as in the case before described) an extended reduced portion near its longitudinal central region, so as to permit communication between the supply and delivery passage-ways, through 30 the ports 38 and 39. In this instance, the region of suitable given pressure with which the passage-way 42, in which the upper extremity of the sleeve 35, is located, communicates (by a passage 43) is not the valve 35 outlet 34, as in Fig. I, but an external one, in this instance the atmosphere. So also, the lower portion 44, of the internal cavity of the sleeve communicates by a passage 45, with a similar external pressure region, so 40 that the valve parts are under substantially balanced pressure. The arrangement of the actuating member or plunger 46, abutment plate 47, spring 48, and cap 49, are substantially similar to those before described; and 45 the general operation of the device will be apparent, it being noted that the conical portion 36, of the sleeve can be brought into absolutely tight contact with the opening in the casing by means of the screw threaded 50 engagement at the region 37.

In the form of the device shown in Fig. V, the general arrangement of the main parts is similar to that of Figs. I, and IV. In this instance, however, the entire sleeve 55 has a plain conical external contour; as shown at 52, and is forced into engagement with the wall of the receiving cavity by means of the threaded cap 51.

Furthermore, the valve body 55, is shown 60 in this instance as integral with its actuating member rod 56, a cylindrical axial extension 57, of reduced diameter, being provided at the upper portion of the valve body, to receive the lower extremity of the spring 65 58, which bears directly upon the shoulder

59, of the valve body, instead of bearing upon an interposed abutment plate. It will be noted, however, that in this instance, the spring 58, is of an inverted conical contour, so that the area of the bearing portion at the 70 lower extremity of the spring is substantially reduced, as compared with the bearing portion at the upper extremity, thus tending to centralize the thrust of the spring against the upper portion of the valve body. 75 In this instance, the passage-way 60, communicates with the internal cavity of the cap 51, by means of the slot, or groove 61, and also communicates with a region of given pressure, in this instance, again, the 80 atmosphere, by means of the passage-way 62. The lower extremity 63, of the opening within the sleeve communicates with said region of pressure by the enlarged passage-way 64, through which the plunger 56, projects at the lower extremity of the sleeve, hence this type of valve is substantially balanced.

The several embodiments of the valve above described (and others which may correspond substantially thereto in principle, though different in detail, and which I desire to include in my claims), are peculiarly adapted to use in the exceptionally severe service which is found in locomotive head 90 lighting. In such valves it is very important to reduce the indeterminate friction to the lowest point, since it is a factor whose intensity varies more or less, depending upon the length of time the valve is in use, 100 the condition of the surfaces which are in active co-operation, the differences due to the quality of water and boiler compounds found in various sections of an extended country like the United States, etc. 105

It will be noted that when a separate plunger rod is employed to actuate the valve body the mechanical friction is reduced by extending said rod up to a point near the 110 top of the body. Moreover, the top end of the valve body is cone-shaped externally and co-operates with a loosely mounted abutment plate, which ensures the application of the spring tension as near as possible 115 in an axial line corresponding to the axis of the valve body, hence there is little or no lateral pressure which would tend to make the valve body bind in moving within the sleeve.

When the plunger rod is made integral 120 with the valve body, as in the case of Fig. V, the bearing region of the spring is centralized by the arrangement shown, to produce a similar result.

Speaking broadly, it may be said that this feature is due to the fact that the force which tends to raise the valve may be considered as applied at, or symmetrically close to the point where the force which tends to resist the raising of the valve is applied. 130

The structural characteristics of the valve body and its relation to the sleeve and the openings, therein, are such as to permit extreme accuracy of control and ensure satisfactory operation under the most varying conditions of internal steam pressure.

Furthermore, for the purposes of assembly, access, repairs and adjustment, etc., the structural organization has great advantages, in that the entire working system can be readily withdrawn by unscrewing the covering cap, and, in the instance shown in Figs. I, and IV, then unscrewing the sleeve to whose upper extremity complete access is thus afforded.

Similarly, the parts can be assembled with great accuracy and without the possibility of mistaken arrangement, even by a careless operator. Thus, referring to Fig. I; in order to adjust the valve for general conditions, remove the cap 13, spring 15, and abutment plate 14, and raise or lower the nut 18, so as to shift the valve body until the shoulder around the projection 24, at the upper extremity of the valve body is level with the top surface Y of the sleeve. This adjustment can be made without having to remove the whole valve structure, or even any of the vital working parts. Moreover, while the shoulder of the valve device 9 is visible at the top Y of the valve case 5 as soon as the cap 13 is removed, the indicator cooperation of valve device and valve case can be utilized by "feeling" (directly or mechanically), even in the dark. It will also be noted that in all the types shown, the drainage naturally follows the course described in connection with Fig. I, so that accumulation of moisture or dripping in the valve is effectually prevented. It will be understood, however, that I do not limit all my claims to such vertical arrangement of the parts.

Having thus described my invention, I claim:

1. The combination of a casing having overlapping isolated passages arranged in different planes and an opening intersecting said passages; a valve mounting structure in said opening comprising a sleeve held firmly seated and fixed by screw threaded engagement of said structure with said casing, said sleeve having ports which communicate with the aforesaid passages in the casing; a valve body longitudinally movable in said sleeve and cooperating with said ports to control the passage of fluid therethrough; and yielding means mounted in said valve mounting structure whereby said valve body is normally urged in one direction in said sleeve.

2. In a controlling valve, the combination of a casing having overlapping isolated passages arranged in different planes and an opening intersecting said passages, two of said passages constituting, respectively, inlet

and outlet passages for the valve, and another being in communication with a suitable pressure region; a valve mounting structure in said opening comprising a sleeve having ports which communicate with the aforesaid inlet and outlet passages, and having its interior in communication, at one end, with said other passage a valve body longitudinally movable in said sleeve and having a reduced portion sufficient in extent to include said ports, one end of said valve body being exposed to the pressure in the interior of said sleeve at the end aforesaid; and an actuating rod for said valve extending out through said mounting structure at the other end of the valve.

3. A device in accordance with claim 2, including a cap separate from said sleeve screwed into the said opening in the casing, and a compression spring acting between said cap and said valve body to urge the latter longitudinally in said sleeve.

4. The combination of a casing having isolated passages arranged in different planes, and having an opening transverse to said passages, said opening comprising a tapered portion, and a cylindrical threaded portion; a sleeve adapted to fit closely within said opening, and having ports which communicate with said passages respectively, said sleeve having a tapered portion adapted to fit within the tapered portion of the opening and having a threaded cylindrical portion adapted to engage the threaded portion of the casing opening; a valve body longitudinally movable within said sleeve, and having a reduced portion sufficient in extent to include said ports; and means for shifting the valve body longitudinally within said sleeve.

5. A valve group comprising the following members in combination; a seat element having an axial opening with lateral ports arranged at different planes; a valve body longitudinally movable within said seat, and having a reduced external portion sufficient in extent to include said ports, said valve body having an axial cavity open at one end and terminating at the other end in a concave tapering surface; an external bearing lug upon the end of said valve body; a plunger fitting loosely within the cavity of the valve body and provided with a reduced extremity adapted to engage centrally within the concave extremity of the cavity; resilient means, operatively engaging said bearing lug, and tending normally to move the valve body in one direction; and positive actuating mechanism, whereby the plunger may be moved to shift the valve body in the opposite direction.

6. The combination of a casing having overlapping isolated passages arranged in different planes and an opening intersecting said passages; a valve mounting structure in

said opening comprising a sleeve held firmly seated and fixed by screw threaded engagement of said structure with said casing, said sleeve having ports which communicate with the aforesaid passages in the casing; a valve body longitudinally movable in said sleeve and cooperating with said ports to control the passage of fluid therethrough; spring means mounted in said valve mounting structure acting on one end of said valve body to urge it longitudinally in said sleeve; and other means for shifting said valve body longitudinally in said sleeve comprising an actuating member projecting from the end of the latter opposite that acted on by said spring means.

7. A valve comprising a valve casing, a valve piston therein and a sliding valve operating stem unconnected with but in contact with said piston and a governor member adapted to contact said valve stem and actuate said valve piston.

8. A governor valve comprising a valve casing a hollow valve piston therein and a valve operating stem surrounded by and in contact with but unconnected with said valve piston, and a yielding member in opposition thereto.

9. In a fluid engine, a valve comprising a valve casing, a plug, a valve operating stem and a valve piston positioned between said plug and said stem and in contact with said stem, said valve piston adapted to be held normally in open position.

35 10. The combination of a casing structure having passage for motive fluid and an intersecting conical bore; a hollow closure for the large end of said bore; a ported sleeve in said bore protruding from its small end; a longitudinally movable valve body in said sleeve, with an endwise extension; and a spring in said closure acting on said extension.

11. The combination of a casing structure having passage for motive fluid and an intersecting bore; a valve mounting in said bore including a ported sleeve and a hollow plug; a longitudinally movable valve body in said sleeve with an endwise extension; and a spring in said plug acting on said extension.

12. The combination of a valve mounting including a ported sleeve and a hollow plug; a longitudinally movable valve body in said sleeve with an endwise extension; a spring in said plug; and a member interposed between said spring and the end of said extension.

13. The combination of a valve casing including a casing structure with passage for motive fluid and an intersecting bore, and a ported valve case in said bore; a closure for one end of said bore; a valve piston in said valve casing within said case; a sliding valve operating stem unconnected but in contact

with said piston, said valve piston being visible at the top of said valve case when said closure is removed, and cooperating with the top of the case as an adjustment indicator; and a governor member adapted to contact said valve stem and actuate said valve piston.

14. The combination of a valve mounting including a ported sleeve and a hollow plug; a longitudinally movable valve body in said sleeve with an endwise extension; a spring in said plug acting on said extension; and a valve operating stem unconnected with but engaging said valve body.

15. The combination of a casing structure having passage for motive fluid and an intersecting bore; a ported valve case in said bore with one end protruding therefrom and having a reduced opening; a longitudinally movable valve body in said case; a spring urging said valve body toward the last-mentioned end of said case; and a valve operating stem extending into said case from said last-mentioned end thereof, with its end engaging said valve body to actuate the latter in opposition to said spring, but unconnected to the valve body.

16. The combination of a valve case with reduced opening at one end; a longitudinally movable valve in said case; and a valve operating stem extending through said reduced opening and engaging said valve body, but unconnected therewith; with means of communication whereby the upper and lower ends of said valve body are exposed to similar pressures.

17. The combination of a casing structure having passage for motive fluid and an intersecting bore; a ported valve case in said bore; a longitudinally movable hollow valve body in said case, open at one end; a spring urging said valve body one way in said case; and a valve operating stem extending into said valve body from its open end and engaging it at the bottom of its cavity.

18. The combination of a valve case; a longitudinally movable hollow valve body therein open at one end, and having an endwise extension at the other end; a spring acting on said extension; and a valve operating stem extending into said valve body from its open end, and engaging it at the bottom of its cavity.

19. The combination of a casing structure having passage for motive fluid and an intersecting bore; a ported valve case in said bore with one end protruding therefrom, and having a reduced opening; a longitudinally movable hollow valve body in said case, open at one end; a spring urging said valve body toward the last-mentioned end of said case; and a valve operating stem extending into said case and said valve body from the protruding end of the case, and en-

erating stem unconnected with but in contact with said piston; and a governor member adapted to contact said valve stem and actuate said valve piston; said valve piston cooperating with the top of the case as an adjustment indicator. 15

20

- gaging the bottom of the cavity of the valve body to actuate the latter in opposition to said spring.
20. The combination of a valve case; a longitudinally movable hollow valve body therein open at one end, and having an interior concave tapered surface at its other end; a spring urging said valve body one way in said case; and a valve operating stem loose in said valve body cavity and engaging its concave end surface to actuate the valve body the other way.

21. The combination of a valve casing; a valve piston therein; a sliding valve op-

In testimony whereof, I have hereunto signed my name at Philadelphia, Pennsylvania, this tenth day of December, 1918.
